ATTORNEYS

UNITED STATES PATENT OFFICE.

CHARLES A. TATUM, OF NEW YORK, N. Y., ASSIGNOR TO WHITALL, TATUM & CO., OF SAME PLACE.

DESIGN FOR A BOTTLE-STOPPER.

SPECIFICATION forming part of Design No. 23,175, dated April 10, 1894.

Application filed March 14, 1894. Serial No. 503,645. Term of patent 14 years.

To all whom it may concern:

Be it known that I, CHARLES A. TATUM, a citizen of the United States, and a resident of the city, county, and State of New York, have invented and produced a new and original Design for Bottle-Stoppers, of which the following is a full, clear, and exact description.

My design consists of a bottle stopper, herein shown and described, of essentially the configuration and ornamentation as illustrated in the accompanying drawings, in which—

Figure 1 is a side view of a bottle stopper in which my design is embodied. Fig. 2 is a plan view of the same.

In the drawings, *a* indicates the stopper proper, *b* a flattened ovoid head or handle extending therefrom and united to the stopper proper by a neck *d*. On each side of the head *b* is a raised oval panel *c*.

What I claim is—

The design for a bottle stopper substantially as shown and described.

CHARLES A. TATUM.
